UNITED STATES PATENT OFFICE.

ARTHUR W. EDWARDS, OF SACRAMENTO, CALIFORNIA.

COMPOSITION WALL FOR CASKETS.

Application filed September 29, 1920. Serial No. 413,614.

To all whom it may concern:

Be it known that I, ARTHUR W. EDWARDS, a citizen of the United States, residing at Sacramento, in the county of Sacramento and State of California, have invented new and useful Improvements in Composition Walls for Caskets, of which the following is a specification.

This invention relates to a burial casket, 10 and more particularly to a composition of material for forming the walls of a casket or other purposes, for which such a composition wall would be suitable.

The object of the invention is to provide 15 such a composition wall for a casket, or for a like purpose, which is extremely inexpensive and light, and yet sufficiently durable for the intended use.

The invention briefly consists in preparing 20 a composition from rice straw, paper pulp and wood pulp and sufficient water to secure the desired consistency. The composition formed is then placed in a mold of the desired shape and subjected to a high degree of pressure, either by a hydraulic or screw press. Also, a reinforcing element may be incorporated if so desired.

The intended use of the invention is illustrated in the accompanying drawings, in 30 which—

Fig. 1 is a cross section of the composition when compressed; and

Fig. 2 is a side elevation of a burial casket with its walls formed of the composition shown in Fig. 1.

Referring further to the drawings, A indicates the composition formed when subjected to pressure and C a casket with composition walls as shown in Fig. 1. The bottom and sides of the casket are preferably formed by one mold and compression.

Any artistic beauty of the casket could be had by forming the molds to give the desired result. The cover is molded separately and preferably the casket and cover are 45 so formed that the casket can be hermetically sealed. The casket may be covered in the usual manner and in appearance would be the same as an expensive casket.

The composition, when placed under pressure, forms a hard substance, not easily dented or broken. The greater the pressure the composition is subjected to, the greater the strength and toughness of the 50 material formed.

A fine mesh wire screen B may also be incorporated in the walls as shown by the drawings to serve as a reinforcement. This element is preferable, but not necessary, as the composition forms a material 55 sufficiently durable and of sufficient strength for the use intended.

While I have shown and described my invention for a particular use, it is to be understood that I am not to be so limited 60 as indicated by the appended claim.

Having thus described my invention, what I claim and desire to secure by Letters Patent is:

A burial casket moulded and compressed 70 to shape of fibrous plastic substance consisting of rice straw, paper and wood pulp, the walls and bottom of said casket having connected sheets of reticulated reinforcing material embedded therein.

In testimony whereof I have hereunto set my hand in the presence of two subscribing witnesses.

ARTHUR W. EDWARDS.

Witnesses:

R. P. TALBOT,
GEORGE L. POPERT.
